UNITED STATES PATENT OFFICE.

TOD J. MELL, OF AKRON, OHIO, ASSIGNOR TO THE B. F. GOODRICH COMPANY, OF NEW YORK, N. Y., A CORPORATION OF NEW YORK.

INTERIOR COVERING STRUCTURE FOR ROOMS AND METHOD OF APPLYING THE SAME.

Application filed October 19, 1925. Serial No. 63,351.

This invention relates to coverings adapted to be used instead of the base-boards commonly applied to the walls of a room adjacent the junction of the wall with the floor, and its chief objects are to provide neatness, ease of application, durability, noiselessness, sanitary characteristics and economy in a structure of this kind. A further object is, in combination with a floor-covering border 10 having different widths along different walls of the room to fill out the spaces between a patterned floor covering and the walls, to provide a wall-base covering adapted to lessen the appearance of inequality in the 15 widths of the floor-covering border.

In accomplishing these objects I employ sheet rubber or the like as a base-covering in combination with fastening means adapted to cover seams or margins of the sheet material, and to coat therewith, by sealing against the resilient and deformable surface of the material, to exclude dirt from the seams and to prevent unsightly crevices. I provide fastening members adapted to be 20 simply and securely anchored in place at the angles of the walls and at the same time to fit resiliently against the base covering at their margins.

The deformable sheet material of the base-covering is preferably formed integral with a covering for a portion of the floor, so that no horizontal seam occurs along the junction of the wall with the floor, and this construction is especially suitable for use upon a wall 30 having a coved toe or base portion joining the floor at an obtuse angle such as to facilitate the removal of dirt from the corner of the two and such as to make a sharp bend or angle in the covering material unnecessary. 35 Forming the wall-base covering integrally and of the same color or design with a floor-covering border portion and avoiding a sharp angle at the junction of the floor and wall also makes less apparent any difference 40 of width between border portions meeting at a corner of the room.

Of the accompanying drawings:

Fig. 1 is a perspective view of parts of the floor and walls of a room having a preferred 50 embodiment of my invention installed therein.

Fig. 2 is a vertical section on line 2—2

of Fig. 1, of the floor, wall and covering structure.

Fig. 3 is a horizontal section on line 3—3 of Fig. 1.

Referring to the drawings, sheets 10, 10, of rubber or the like, are applied to the base portions of the walls A, B, and C, and along their upper margins are clamped in place by 60 finishing strips 11, 11, of metal or other suitable material, said strips being secured by screws 12, 12, driven through the plaster, 13, and into the lath, 14, 14. The finishing strips 11 are preferably so formed as to press 65 tightly along their lower margins against the respective sheets 10, the resilience of the material of the latter causing it to conform to the finishing strip and thus provide a continuous fit along the strip.

At the junction of the sheets 10 in a recess corner, as at the junction of the walls A and B, the vertical seam is covered and the vertical margins of the sheets 10 are clamped against the respective walls by a finishing member or plate 15 drawn into the corner by screws 16, 16, which are driven, preferably in a plane bisecting the angle of the walls, into the wall structure, the plate being so formed as to fit into the corner at its upper 70 end, above the sheets 10, and to press, but only along its margin, against both of the adjacent sheets 10 by reason of its movement into the corner, as shown clearly in Fig. 3.

At a projecting corner, as at the junction 85 of the walls B and C, the vertical seam of the sheets 10 is covered and the vertical margins of the sheets are clamped against the respective walls by a finishing member or plate 17 drawn up by screws 18, 18, which are driven 90 into the wall structure, this plate being so formed as to fit against the walls at its upper end and to press, but only along its margin, against both of the adjacent sheets 10 as it is drawn onto the corner of the wall structure by the setting up of the screws 18.

The base-covering sheets 10 are preferably formed integrally with respective portions 10^a, 10^a, adapted to lie horizontally upon the floor 19 of the room to constitute 100 a border for the central or main floor-covering 20. Thus the seams 21, 21, between the border portions 10^a and the main floor covering 20, occur at a distance from the walls

- and not in angles of the floor and walls. This permits easy and close fitting of the seams and provides a continuous, seamless covering from the seam 21 up onto the vertical wall, as shown clearly in Fig. 2. The angle at the junction of the floor and wall is preferably filled with a concave molding or cove 22 (Fig. 2) underlying the sheet 10—10^a, to avoid a sharp angle in the latter, and in this case the plates 15 and 17 are preferably formed with margins correspondingly curved at their lower ends and are adapted to overlie the respective seams throughout the region of the cove 22.
- 15 The border portions 10^a of the sheets 10, although of different widths because of the different spaces between the patterned floor covering 20 and the walls, may be easily cut so as to abut each other at their adjacent ends in close-fitting seams as at 23, 24, such seams being comparatively short and being in the horizontal or floor-covering portions of the sheets, so that only a simple, straight cut, at the proper angle, depending upon the relative widths of the portions 10^a, is required. The main floor covering 20 and the border portions 10^a of the sheets 10 are preferably secured to the floor 19 by a layer 25 of a suitable adhesive.
- 30 Accurate cutting of the end margins of the sheets 10, which would be difficult because of the comparatively great length of the cut and because of the curvature imposed by the cove 22, is rendered unnecessary, 35 since these margins are hidden and substantially sealed off from the interior of the room by the contact of the margins of the corner plate 15 or 17 with the sheets 10. The portions 10 and 10^a of the integral sheets are preferably of the same color or 40 design, so that no distinct line of demarcation occurs therein so close to the seam 21 as to accentuate the difference in width of the spaces outside of the main floor covering 45 20 which are filled in by the said portions 10^a, and especially when such line of demarcation is further avoided by the use of the cove 22.
- The several advantages obtained will be 50 clear in view of the statement of objects set out above.
- My invention is susceptible of modification within its scope and I do not wholly limit my claims to the specific construction or 55 materials or to the exact procedure herein described.
- I claim:
1. A wall-base covering comprising a sheet of material having substantial deformability and resilience in the direction of the thickness of the sheet, a finishing member overlapping a margin thereof, and fastening means holding said member in intimate, deforming contact with said sheet, 60 the said fastening means being engaged with the underlying structure of the wall and adapted for drawing the finishing member against the deformable sheet material.
  2. In combination with walls having surfaces meeting each other to form a corner, a wall covering structure comprising sheet material covering the walls adjacent the corner, a finishing member adapted to fit against the sheet material at opposite sides of the corner, and fastening means adapted to draw the finishing member toward the corner in a direction at substantially equal angles to the walls, the finishing member being so formed as to bear primarily at its margins against the sheet material. 70
  3. In combination with a wall, a covering therefor comprising a sheet of rubber, a finishing member overlapping a margin thereof, and fastening means holding said finishing member to the wall and thereby holding the sheet of rubber under such compression between the two as to provide a tight, continuous fit of the rubber and the finishing member along a margin of the latter, the said fastening means being engaged with the underlying structure of the wall and adapted for drawing the finishing member against the sheet of rubber. 80
  4. In combination with a wall, a covering therefor comprising a sheet of material having substantial compressibility and resilience in the direction of the thickness of the sheet, a finishing member overlapping a margin of the sheet and so formed as to bear primarily along one of its margins against the sheets while bearing directly against the wall at another of its margins, and means for holding it to the wall with its first mentioned margin pressing the resilient sheet against the wall, the said fastening means being engaged with the underlying structure of the wall and adapted for drawing the finishing member against the deformable sheet material. 90
  5. In combination with two walls having surfaces meeting each other to form a corner, a wall-covering structure comprising sheet material covering the walls adjacent the corner and having substantial deformability and resilience in the direction of the thickness of the sheet, a finishing member bearing against the two walls at the corner and overlapping and compressing a margin of the sheet material, and means for holding the finishing member to the walls, the said fastening means being engaged with the underlying structure of the wall and adapted for drawing the finishing member against the deformable sheet material. 100
  6. In combination with a floor and a wall rising therefrom, a wall-base covering comprising flexible sheet material covering the base portion of the wall and extending integrally onto the floor, the said material having substantial compressibility and re- 110

silence in the direction of the thickness of the sheet, a finishing member overlapping and compressing a margin of the sheet lying against the wall, and means for holding the finishing member to the wall with its margin compressing the sheet against the wall.

7. A combination as defined in claim 6 in which the corner formed by the wall and floor is rounded.

8. In combination with a floor and two walls rising therefrom and meeting each other at an angle to form a corner, flexible, cushioning members of sheet material cover-

ing the respective walls adjacent the corner 15 and having portions extending integrally onto the floor, the said portions upon the floor being fitted to each other in a butt seam, the corners formed by the respective walls and the floor being rounded and the said 20 portions extending onto the floor being of unequal widths but having straight edges meeting each other at the end of the butt seam.

In witness whereof I have hereunto set 25 my hand this 10th day of October, 1925.

TOD J. MELL.
